Primary Examiner — Susan Bennett Hattan*Assistant Examiner* — Vy Koenig(74) *Attorney, Agent, or Firm* — Andrus, Sceales, Starke & Sawall, LLP(57) **CLAIM**

The ornamental design for a tablet chair with book rack, as shown and described.

DESCRIPTION

FIG. 1 is an isometric view of a tablet chair with a book rack incorporating our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a top view taken along line 7-7 of FIG. 3.

The portions shown in phantom illustrate environment and form no part of the claimed design.
